WINDOW

Alexander Kalla, Sr., Linden, N. J.

Application May 8, 1936, Serial No. 78,713

1 Claim. (Cl. 20—49)

The present invention relates to windows and more particularly to a window embodying novel means whereby the upper and lower sashes are adapted to be mounted in a window frame for vertical sliding movement therein and also for forward swinging movement relative thereto.

One of the objects of the invention is to provide a simplified construction to accomplish the above objects and also to permit the sashes to be quickly removed from the window frame when desired.

Still a further aim is to construct a sash which is both vertically slideable and capable of being swung forwardly out of the frame, said sash embodying means which functions as a pivot, the latter designed so that it may serve to disconnect the sash at one point for removal of the latter from the window frame.

The above and other aims and objects will be apparent from the detailed description hereinafter appearing when taken in conjunction with the appended drawings forming part hereof and to which reference is now made and in which:

25 Fig. 1 is a front elevational view of a standard window frame having the novel sash construction mounted therein;

Fig. 2 is a sectional view taken on line 2—2 of Fig. 1;

30 Fig. 3 is a sectional view taken on line 3—3 of Fig. 1;

Fig. 4 is a view similar to Fig. 2, with the sashes removed, showing the groove for receiving a rod carrying metallic weather strips;

35 Fig. 5 is a front elevational view of the weather stripping rod and upper and lower slideable sash bars associated therewith;

Fig. 6 is a side elevational view of the structure of Fig. 5;

40 Fig. 7 is a detail vertical sectional view centrally through the top portion of one of the sash bars;

Fig. 8 is a sectional view taken on the line 8—8 of Fig. 5;

45 Fig. 9 is a detail sectional view showing a latch for connecting a sash and one of its slideable bars;

Fig. 10 is a detail sectional view of a pivot fitting and means whereby the sash may be disconnected from one of its slideable bars.

Referring now to Fig. 1 of the drawings, it will be seen that the window constituting the present invention comprises a frame generally designated as 1, said frame including a stool 2, 55 vertical side members 4 and 5, and a top cross

member 6. Each vertical side member has its inner surface stepped (see Fig. 3), to provide vertical channels 7, 8 and a groove 9, which receives a removable wooden bar 10 which has upper and lower metallic weather strips 11 and 12 secured thereto on opposed side faces thereof as by nails 13 or the like. The window frame just described is of conventional or standard construction with the exception that the removable wooden bar 10 is normally permanently fixed on the inner surface of the frame and provides a dividing guide forming channels 7 and 8 in which the sashes move vertically. It will be understood that each of the opposed inner faces of the frame is of identical construction, also that the sashes to be hereinafter described are of like construction at their vertical side edges which cooperate with the channels and wooden bar 10.

The channels 7 and 8 are each provided at the upper ends thereof with pulleys 14 and 15 on which are mounted cables 16 and 17 secured at one end to sash weight (not shown), and, within the frame, cable 16 is detachably secured to a removable, slideable, upper, sash bar 18 and cable 17 to a similar lower bar 19. An upper sash 20 is pivotally and removably secured to sash bar 18 and a lower sash 21 is similarly secured to sash bar 19, in a manner to be shortly described.

Referring for the moment to Figures 5, 6 and 8 and to sash bars 18 and 19, it will be noted that bar 18 is substantially square in cross section and is provided at one corner thereof with a vertical groove or slot 22 which receives the metallic strip 11. Thus after wooden guide bar 10 is fixed in groove 9, and bar 18 mounted so that groove 22 receives strip 11, the latter will function to guide bar 18 in its vertical sliding movement within channel 7 of the window frame. The top of bar 18 is provided with a groove 23 within which a knotted end 24 of cable 16 is detachably received in a manner well known in the art. A metallic pivot member 25 secured to the top of bar 18 has a vertical portion 26 extending into groove 23, the horizontal section 27 contacting the top of bar 18, and an inner vertical portion 28 which terminates in a hook 29. Sections 26 and 28 are provided with aligned apertures 30 (see Fig. 10) for a purpose to be referred to later.

A side face of bar 18 is cut away as at 31 to receive a pair of arms 32, 33 pivoted to each other at 34, and to bar 18 within the cut-away portion 31, at 35. The bottom face 36 of bar 18 is provided with a slit 37 within which is pivoted as at 38, a latch bar 39.

By reference to Figs. 3, 9 and 10 it will be

noted that one end of the upper surface of sash 20 is hollowed out to form an elongated groove 41. A pivot member 42 has a horizontal plate portion 43 and a vertical section 44 which is received within hook 29 of cooperating pivot member 25. A slideable pin 45 constitutes a pivot for members 25 and 42. However, when pin 45 is moved to the right, as seen in Fig. 10, within groove 41, said pin will be withdrawn from aperture 30 in bar 18 into which it extends, so that sash 20 may be disconnected therefrom at this point. The lower face of sash 20 at one end thereof is provided with a slit 46 for receiving latch bar 39 so that the sash will be connected to bar 18. When the latch is moved downwardly about pivot 38 the sash and its bar are disconnected at this point. Arm 32 is provided with an aperture 32', at one end thereof (Fig. 5), for detachable connection to a removable screw 47 carried on the inner face of sash 20. It is desired to point out that each of the inner faces of sashes 20 and 21 are of identical construction; that bars 18 and 19 are similar only in that they are mirror images of each other; that sash 21 has a pair of pivot members at its opposed faces as at 50, 51; that sash 21 has two latch members, as at 60, 61. In other words there are two bars 18 for sash 20; two bars 19 for sash 21, and that the structures are duplicated adjacent each edge of the respective sashes.

Mode of operation

In the position of the sashes shown in Fig. 1, they may be each moved vertically up and down in a normal manner, bars 18 and 19 being guided in channels 7 and 8 by bar 10. Should it now be desired to swing the sash forwardly, it merely becomes necessary to raise same a trifle above stool 2, then to insert a hand within a finger hold 46' (Fig. 9) to grasp latch 39 and swing same downwardly about pivot 38. This is done at the opposed ends of the sash and the latter may now be pulled forwardly, pivoting on its pivot pins 45. The sash is held in its forwardly swung position

by pivot arms 32, 33, as shown in Fig. 2. Now should it be further desired to remove a sash or sashes, pivot pins 45 are moved inwardly toward each other out of aperture 30. By means of a screw driver or the like, screws 47 are unscrewed to pass through aperture 32' in arm 32. After this has been done each of the sashes becomes separable from the respective bars 18 or 19. The latter can then be removed by withdrawing same so that metallic strips 11 and 12 no longer fit within groove 22 of said bars. Finally bar 10, which carries metallic strips 11 and 12, may be withdrawn from its groove 9.

It will thus be seen that there has been provided a novel window structure which is readily disassembled, and well adapted to perform its intended functions. Standard window frames may be easily modified to accommodate the novel sash construction of this invention. Further, when the sashes, the slideable sash bars 18 and 19, and weather strip bar are removed, the interior of the frame and the various parts of the window proper may be readily painted or decorated.

While the invention has been described in somewhat great detail, it will be appreciated that various changes and modifications thereof can be made and it is my intention to be limited in this respect only as may be necessary by the scope of the claim hereto appended.

I claim:—

In a window, a frame having each inner face provided with a vertical groove, a removable bar having a metallic strip secured thereto mounted in said groove, a slideable sash bar having a longitudinal slot, said metallic strip extending into said slot to guide said sash bar, a sash, unitary means pivotally and releasably connecting the upper edge of the sash to the top of said sash bar, means pivotally and releasably connecting an intermediate portion of the sash bar to the sash, and means releasably securing the bottom of the sash bar to the sash.

ALEXANDER KALLA, SR.
